A. S. RAMAGE

APPARATUS AND PROCESS FOR DISTILLATION OF COAL

Filed April 9, 1923

Fig. 1.

UNITED STATES PATENT OFFICE.

ALEXANDER S. RAMAGE, OF DETROIT, MICHIGAN.

APPARATUS AND PROCESS FOR DISTILLATION OF COAL.

Application filed April 9, 1923. Serial No. 630,910.

To all whom it may concern:

Be it known that I, ALEXANDER S. RAMAGE, a citizen of the United States, residing at Detroit, in the county of Wayne and 55
5 State of Michigan, have invented certain new and useful Improvements in Apparatus and Processes for Distillation of Coal, of which the following is a specification.

This invention relates to a type of apparatus and to a process for the low temperature distillation of bituminous materials such as coal, an object of the invention being the production of the maximum yield of so-called low temperature oil, or low temperature 60
10 tar oil of a paraffinoid character.

A further object of the invention is the maximum utilization of the sensible heat of the blow gases and water gas, thereby making it possible to complete the distillation without the use of other heat.

A further object of the invention is a maximum conversion of the nitrogen content of the material to ammonia which may be recovered from the distillation gases in the 65
20 well known manner.

A further object of the invention is to provide apparatus so designed and constructed as to efficiently utilize the sensible heat of the gases for heating the material 70
30 to be distilled and to so apply the heat as to remove the maximum proportion of the volatile matter from the material to be distilled at the lowest possible temperature and discharge the same immediately into a cooler 75
35 region.

In many of the known processes for the distillation of coal the object is to produce the maximum quantity of gaseous product, and to this end the distillation products are 80
40 passed through a hotter region than that in which they are generated for the purpose of cracking the heavy hydrocarbons and producing gaseous products therefrom. The result, in addition to the gas produced, is 85
45 a tar very similar to the usual gas works tar, containing aromatics, phenol, naphthalene and anthracene, while what I aim to produce is a tar oil consisting of light and heavy boiling olefines, homologues of phenol, 90
50 hydrocarbons of the paraffinoid character and solid paraffine but practically no phenol, naphthalene or anthracene. Such a tar oil is known as low temperature oil and the

lower the temperature of distillation and the less the vapors are exposed to highly 55
heated surfaces the greater is the yield of the light boiling product.

The accompanying drawings illustrate one form of apparatus embodying my invention and suitable for carrying out the 60
60 process thereof.

Referring to the drawings,

Figs. 1 and 2 are vertical sections through the apparatus in planes at right angles to each other.

Fig. 3 is a horizontal section through the retort above the line 1—1, and

Fig. 4 is a horizontal section of the retort below the line 1—1.

The retort comprises the upper part A 70
above the line 1—1, the lower part B below the line 1—1, and the generator C.

The outer walls of the retort are built up in the customary manner of an outer layer 1 and an inner layer 2 of fire brick, 75
75 and an intermediate layer 3 of refractory heat insulating material such as "celite." The inner wall 4 of the upper part A of the retort is made of cast iron and is spaced 80
from the outer wall a distance of about 5 inches and carries on its outer surface horizontal fins 5 eight inches wide and spaced about six inches apart. The outer edges of the fins 5 extend into the layer 2 of the outer wall of the retort forming channels. At 85
one corner of the upper part A of the retort the alternate fins are provided with openings 6 and 7, respectively, about four by five 90
inches square separated by the vertical fin 8 (see Fig. 3), thus connecting the channels in series. The uppermost channel communicates with the pipe 10 through an opening 36 in the side thereof. The upper part A of 95
the retort preferably is about twelve inches thick and four feet wide at the top and sixteen inches thick by four and one-half feet wide at the bottom and about ten feet in height. The vertical hollow partition 9 which is about four inches thick and stands 100
perpendicular to the end walls of the retort divides the upper part A of the retort into two equal sections. The partition 9 is closed over the top and bottom, the top closure having a central peak to prevent the accumulation of coal thereon, and is provided 105
with a lateral opening 21 near the top com-

municating with the exit pipe 10 and a lateral opening 11 near the bottom communicating with channels surrounding the lower part of the retort to be described herein-
5 after. Within the partition 9 are shelves 12 provided with the staggered openings 13, 14.

The inner wall 15 of the lower part B of the retort is made of fire clay or like refractory material and is spaced about five
10 inches from the outer wall of the retort and carries on its outer surface the eight-inch fins 16 spaced about six inches apart, extending into the layer 2 of the outer wall of the retort. The channels formed by the
15 fins 16 are divided into two groups by vertical partitions 17 and 18 at two opposite corners of the retort, one group comprising the channels across one end and along one side of the retort and the other group comprising the channels across the other end and along the other side of the retort (see Fig. 4). The alternate fins of one of said groups are provided with openings 19 and 19', respectively, and the alternate fins of
20 the other group are provided with openings 20 and 20', respectively, thus connecting the channels of each group in series. One of said groups of channels communicates with the hollow partition 9 through the
25 opening 11, while the other group of channels communicates with the channels formed by the fins 5 surrounding the upper part A of the retort through the opening in the uppermost fin 16. The lower part
30 B of the retort is about ten feet in height.

The channel construction and arrangement described above is preferred from a structural standpoint, although as will be apparent the same purpose will be served
40 by forming the fins at such a pitch or inclination, instead of horizontally, as to give a continuous channel around the retort and such a construction is embraced by my invention.

45 The generator C comprises a combustion and fuel chamber 23, a grate 24, poker holes 25, a clinker door 26, an air supply pipe 27 and a steam supply pipe 28. The fuel chamber 23 communicates directly with the interior of the retort and with the two groups of channels surrounding the lower part B of the retort through the openings 29 and 30.

55 The interior of the retort at the top communicates with the exit pipe 31.

On the upper end of the retort is the feed hopper 32 having the two chutes 33 and 34 for supplying the two sections of the upper part A of the retort. In practice
60 it may be desirable to construct a plurality of retorts in a bench.

The operation of the process in the apparatus described is as follows:

65 Assuming that the operation of the retort has been started and that the genera-

tor C contains coke from which practically all volatile matter has been distilled, the lower part B of the retort contains partially distilled coke and the upper part A of the retort contains green coal, the mass of coke in C is first heated to a high temperature by blowing air in through the pipe 27, the resulting blow gases passing through the openings 29 and 30 and upwardly through the two groups of channels surrounding the lower part B of the retort, the gases from one of said groups of channels passing on through the channels around the upper part A of the retort and out through the exit pipe 10, while the gases from the other of said groups of channels passes through the partition 9 and finally out through the exit pipe 10. The poker holes 25 admit an auxiliary supply of air insuring complete combustion of the blow gases. The time of blowing with air ordinarily is about 2 minutes but is variable and should be regulated so that the gases leaving the generator are at a temperature of about 1600° F. and about 900° F. at the
70 exit pipe 10. If the temperature at the exit is greater than 900° F. the rate at which the air is supplied is reduced or vice versa, but it is desirable to use about the same quantity of air during each blow period. The air blast is then shut off and steam superheated to about 700° F. by the waste blow gases discharged from the exit pipe 10, is supplied through the pipe 28. The steam blast ordinarily is continued for
75 about eight minutes, the valve 35 during this period being in position to close the exit pipe 10 and open the exit pipe 31, thus forcing the water gas to pass upwardly through the contents of the retort and finally out through the pipe 31 with the distillation products to suitable means not shown for the recovery of the condensable and the gaseous products. The cycle of air and
80 steam blasting is repeated continuously and
85 the steam blast ordinarily is continued for about eight minutes, the valve 35 during this period being in position to close the exit pipe 10 and open the exit pipe 31, thus forcing the water gas to pass upwardly through the contents of the retort and finally out through the pipe 31 with the distillation products to suitable means not shown for the recovery of the condensable and the gaseous products. The cycle of air and
90 steam blasting is repeated continuously and
95 the steam blast ordinarily is continued for about eight minutes, the valve 35 during this period being in position to close the exit pipe 10 and open the exit pipe 31, thus forcing the water gas to pass upwardly through the contents of the retort and finally out through the pipe 31 with the distillation products to suitable means not shown for the recovery of the condensable and the gaseous products. The cycle of air and
100 steam blasting is repeated continuously and
105 the steam blast ordinarily is continued for about eight minutes, the valve 35 during this period being in position to close the exit pipe 10 and open the exit pipe 31, thus forcing the water gas to pass upwardly through the contents of the retort and finally out through the pipe 31 with the distillation products to suitable means not shown for the recovery of the condensable and the gaseous products. The cycle of air and
110 steam blasting is repeated continuously and
115 the steam blast ordinarily is continued for about eight minutes, the valve 35 during this period being in position to close the exit pipe 10 and open the exit pipe 31, thus forcing the water gas to pass upwardly through the contents of the retort and finally out through the pipe 31 with the distillation products to suitable means not shown for the recovery of the condensable and the gaseous products. The cycle of air and
120 steam blasting is repeated continuously and
125 the steam blast ordinarily is continued for about eight minutes, the valve 35 during this period being in position to close the exit pipe 10 and open the exit pipe 31, thus forcing the water gas to pass upwardly through the contents of the retort and finally out through the pipe 31 with the distillation products to suitable means not shown for the recovery of the condensable and the gaseous products. The cycle of air and
130 steam blasting is repeated continuously and
135 the steam blast ordinarily is continued for about eight minutes, the valve 35 during this period being in position to close the exit pipe 10 and open the exit pipe 31, thus forcing the water gas to pass upwardly through the contents of the retort and finally out through the pipe 31 with the distillation products to suitable means not shown for the recovery of the condensable and the gaseous products. The cycle of air and

140 The accomplishment of the objects of my invention by the process and apparatus described is dependent upon several features, perhaps the most important of which are the following:
145 The coal when it is first exposed to a distilling temperature assumes a pasty condition and is a very poor conductor of heat. In order to heat the coal in this condition and distill its volatile content at the minimum temperature and without local overheating and cracking of the hydrocarbon products it is necessary to heat it uniformly from a source of heat at not too high a temperature. This condition is attained in accordance with my invention by exposing the coal during the initial stage of its distillation in a relatively thin layer to the heat transmitted through the walls of the retort

from the relatively cool heating gases. At the top of the retort the blow gases are coolest and the body of coal is thinnest, being only about four inches thick and it is 5 heated from both sides so that the heat is forced to travel through the coal a distance of only about two inches. As the coal passes downwardly in the retort and the distillation proceeds it becomes less pasty and 10 a better conductor of heat, and the thickness of the body of coal therefore is gradually increased to about six inches by the time it reaches the bottom of the upper part A of the retort. By the time the coal reaches 15 the lower part B of the retort about 70 percent of its volatile content is distilled, and it is no longer pasty and is a fairly good conductor of heat. The completion of the distillation therefore is economically carried 20 out in the lower part B of the retort in which a fairly massive body of the coal about sixteen inches thick is exposed to the heat transmitted through the wall 15 from the relatively hot blow gases. By the time 25 the coal reaches the generator C the distillation is substantially complete.

In addition to the advantageous application of the heat to the coal and the distillation of the maximum quantity of its volatile content at the lowest possible temperature as described, I have also provided for the efficient utilization of the sensible heat of the blow gases and water gas not only by bringing the coal into heat transfer relation thereto in relatively thin layers but also by the described arrangement of the channels through which the gases are passed. I have found that in coal distillation a heating gas passed through a straight conduit 30 of reasonable length in heat transfer relation to the body of coal at a rate of 200 feet per second will not efficiently transfer its sensible heat to the coal. In my process and apparatus therefore I have provided tortuous passages for the gases and so control their rate of flow that the temperature of the exit gases is not substantially in excess of 900° F. In this way a sufficient transfer of heat from the gases to the coal 35 is secured to accomplish the complete distillation of the coal by the sensible heat of the gases produced in the distillation without other heat.

Thus it will be seen that I have provided 40 apparatus and a process for the distillation of coal in which the heat of the blow gases and the water gas is efficiently utilized; and in which the maximum proportion of the volatile matter in the coal is distilled at the 45 lowest temperature and removed from the heating zone without being exposed to a temperature higher than that at which it is distilled. These features contribute both to the minimizing of the cost of operation and 50 to the production of the maximum yield of

the desired low temperature distillation products, that is, the low temperature oil and combined nitrogen in the form of ammonia.

I claim:

1. Apparatus for the distillation of coal, comprising a vertical retort, gas conduits surrounding said retort, and a hollow partition having transverse communicating gas conduits in the upper part only of said retort. 70

2. Apparatus for the distillation of coal, comprising a vertical retort, a hollow partition in the upper part of said retort, a group of gas conduits embracing a portion 80 of the outer wall of the lower part of said retort communicating with said hollow partition, gas conduits surrounding the upper part of said retort, and a second group of gas conduits embracing another portion of 85 the outer wall of the lower part of said retort and communicating with said gas conduits surrounding the upper part of the retort.

3. Apparatus for the distillation of coal comprising a vertical retort, a hollow partition in the upper part only of said retort, gas conduits embracing said upper part of the retort, gas conduits embracing the lower part of the retort, said last named conduits 90 communicating with said conduits embracing the upper part of the retort and with said hollow partition. 95

4. Process for the distillation of coal which comprises establishing a column of material ranging in composition from coke substantially free of volatile matter at one end to green coal at the other end in contact with heat transmitting walls, feeding green coal to said column at said last named end and withdrawing ash from said column at said first named end, the maximum distance of material from said walls within that zone of the column containing more than 30 per cent of its original volatile content ranging from about three inches at the point in said zone at which the material has the smallest volatile content to about two inches at the point in said zone at 100 which the material has the greatest volatile content, and alternately and successively blasting said coke with air and passing the resulting gases in tortuous paths in contact with said walls, and blowing the incandescent coke with steam and passing the resulting hot gases through said column of material. 105 110 115

5. Process for the distillation of coal comprising establishing a column of material containing from about 30 per cent of its original volatile content at one end to 100 per cent of its volatile content at its other end in contact with heat transmitting walls, the maximum distance of material in said 120 125 130

column from said walls being about three inches, and passing hot gases in tortuous paths in contact with said walls in the direction of said material containing 100 per cent of its original volatile content, and regulating the temperature and rate of flow of said gases so that the temperature there-

of in heat transfer relation to said material containing 100 per cent of its original volatile content is not substantially in excess of 900° F. ¹⁰

In testimony whereof, I affix my signature.

ALEXANDER S. RAMAGE.
